P. A. POWERS

SOCKET AND REFLECTOR CONSTRUCTION

Filed June 29, 1925

INVENTOR:
Percival A. Powers

By Jones, Gaddington, Ames & Nichols
Attn: G. J. Jones

UNITED STATES PATENT OFFICE.

PERCIVAL A. POWERS, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SOCKET AND REFLECTOR CONSTRUCTION.

Application filed June 29, 1925. Serial No. 40,249.

My invention relates to a socket and reflector construction and more particularly to a weatherproof socket and reflector construction suitable for outdoor use.

5 One of the objects of my invention is to provide such a construction which can be made cheaply and can be readily wired and which will be durable and efficient.

Further objects will appear from the description and claim.

10 In the drawings, in which my invention is illustrated—

Figure 1 is a side view showing the socket and reflector supported on a horizontally 15 extending pipe;

Fig. 2 is a vertical section through the socket and reflector;

Fig. 3 is a section on the line 3—3 of Fig. 2; and

20 Fig. 4 is a plan view of the socket interior.

Referring to the drawings in detail, the construction shown comprises a lamp socket interior 1, a casing 2 having an opening in 25 its top through which a socket interior may be inserted, a cap 3 for said casing, a reflector 4 secured to the lower edge of the casing 2, the nipple 5 secured to the side of the casing, and a pipe 6 for the wiring, 30 screwed into the nipple 5.

The socket interior construction comprises an insulating base 7, shell and center contacts 8 and 9 respectively mounted thereon, and wiring terminals 10 and 11 on the upper 35 side of the insulating base for the shell and center contacts respectively. The insulating base is provided with an outwardly extending arcuate flange 12 at its upper end which rests on an inwardly extending annular 40 flange 13 on the casing. The insulating base is further provided with a positioning lug 14 which fits in a positioning notch 15 in the casing flange. The upper end of the casing is screw-threaded at 16 to receive the screw-threaded portion 17 of the cap 3. The nip-

ple 5 is secured to the casing in any suitable manner by the use of washers 18 and a nut 19 screwed on the outside of the nipple.

In wiring, the cap 3 is removed from the casing 2, the insulating base 7 is slipped 50 upwardly out of the casing, the wires are drawn in through the nipple, and secured to the wiring terminals 10 and 11, and the base 7 is then slipped back into the casing and the cap 3 screwed on. The cap fits snugly 55 against the upper edge of the insulating base and assists in holding it in position.

While I have shown but one form of my invention, it is to be understood that I do not desire to limit myself to this particular 60 construction since many changes and modifications may be made therein without departure from the scope of the following claim.

Having thus described my invention, what 65 I claim as new and desire to secure by Letters Patent of the U. S. is:

A socket and reflector construction comprising an insulating base, wiring terminals and lamp receptacle contacts mounted therein, a casing for said base, a reflector secured to the lower end of said casing, said casing having a screw threaded portion and an open top through which said base may be inserted into said casing, said casing having 70 an inwardly extending flange above said screw threaded portion, and said base having an outwardly extending flange above and resting on said first flange, a cap screwed on to said casing above and covering said 75 base and serving to force the flange on the base against the flange on the casing and a nipple secured to the side of said casing having a passage for the wires leading to said wiring terminals, said terminals being 80 located on the upper side of said base and exposed when said cap is removed.

In witness whereof, I have hereunto subscribed my name.

PERCIVAL A. POWERS.
